United States Patent Office

Des. 183,237
Patented July 22, 1958

183,237

DRILL BIT

Thomas W. Aven, Jr., Garland, Tex., assignor of one-third to Thomas D. Copeland, Jr., Garland, Tex., an individual

Application September 16, 1955, Serial No. 37,963

Term of patent 14 years

(Cl. D54—4)

Fig. 1 is a top plan view of a drill bit showing my new design;

Fig. 2 is a side elevational view thereof to a larger scale;

Fig. 3 is a front elevational view also to a larger scale; and

Fig. 4 is a bottom plan view.

I claim:

The ornamental design for a drill bit, as shown.
